TOBACCO LOOPING MACHINE

Delbert R. Dinkins, East Bend, N. C., assignor of
one-half to Briggs-Shaffner Company, Win-
ston-Salem, N. C., a corporation of North Car-
olina

Application May 3, 1937, Serial No. 140,553

9 Claims. (Cl. 131—21)

This invention relates to new and useful im-
provements in machines for looping tobacco
hands.

The principal object of the invention is to pro-
vide a support for the tobacco hands and a looping
mechanism which are relatively movable
whereby the hands may be successively placed on
the support and looped together by a connected
series of enchain loops.

10 Another object of the invention lies in the
provision of a carriage which supports the looping
mechanism and which is movable step-by-
step relative to the support for the tobacco hands
whereby the enchain loops will be formed
15 around the successively placed hands subsequent
to the feeding movements of the carriage.

With these and other objects in view which
will more fully appear, the nature of the invention
20 will be more clearly understood by following
the description, the appended claims, and the
several views illustrated in the accompanying
drawings.

In the drawings:—

Figure 1 is a top plan view of a machine con-
25 structed in accordance with my invention, the
view showing the carriage at the end of a feed
movement and the needle at the rear end of its
stroke.

Figure 2 is a front elevation thereof.

30 Figure 3 is a vertical cross-section taken on the
line 3—3 of Figure 2.

Figure 4 is an enlarged detail section of the
carriage feed pawl mechanism.

Figure 5 is an enlarged detail section taken on
35 the line 5—5 of Figure 1.

Figure 6 is an enlarged front elevation of the
needle plate, the needle being shown in section.

Figure 7 is an enlarged vertical section showing
the needle and the needle plate.

40 Figure 8 is an enlarged vertical section taken
on the line 8—8 of Figure 1.

Figure 9 is an enlarged vertical section taken
on the line 9—9 of Figure 1.

45 Figure 10 is an enlarged top plan view of the
spreader.

Figure 11 is a front elevation thereof.

Figure 12 is a plan view showing more or less
diagrammatically the positions of the needle and
50 spreader when the needle is partaking of its loop
shedding movement.

Figure 13 is a similar view but showing the
needle at the end of its loop shedding stroke and
subsequent to the feed travel of the carriage,
55 and

Figure 14 is a perspective view of the left hand
end of the supporting rod.

Like reference numerals designate correspond-
ing parts throughout the several figures of the
drawings.

Referring to the drawings, the invention in-
cludes a stationary track A, a horizontal support-
ing rod B located in front of the track for sup-
porting the looped tobacco hands C, a carriage
D which is intermittently moved along the rails, 10
a carriage feeding means E, and a thread loop-
ing mechanism F mounted on the carriage for
forming a series of connected single thread loops
around the tobacco hands.

The track A is of indeterminate length and 15
comprises spaced upper and lower horizontal rails
5 and 6 of angle iron construction which are se-
cured together by vertical tie rods 7. The track
is supported at its ends on posts 8 by means of
screws 9 which pass through openings in the 20
rails, one only of said posts being shown. It
will be noted that the upper rail 5 includes an
upwardly projecting flange 10, and that the
lower rail includes a downwardly projecting
flange 11.

25 The supporting rod B is substantially coexten-
sive in length with the track A, and is mounted
at each end on the lower rail 6 of said track
through the medium of a forwardly extending
bracket arm 12 secured to the rail, the forward 30
end of the arm being provided with spaced ver-
tical guides 13, 13 between which is mounted a
vertical arm 14 depending from the rod, said
arm 14 having a bolt and slot connection 15 with
the bracket arm whereby the rod may be adjusted 35
vertically to suit working conditions.

The tobacco hands C are preferably positioned
alternately on opposite sides of the supporting
rod B and are retained in said positions by a
connected series of enchain loops 16 formed by 40
the looping mechanism F from a single thread
or twine 17, the supply of which is located with-
in a container 18 mounted on the carriage D.

The carriage D includes a horizontal flat plate
19 which is disposed above the track A and pro-
jects forwardly thereof above the supporting rod 45
B. Rigidly secured to the under face of the car-
riage plate 19 adjacent the rear corners thereof
are bearing blocks 20, 20 which rest upon and
have sliding contact with the upper edge of the 50
vertical flange 10 of the upper rail 5. Bearing
rollers 21, 21 are mounted on the ends of the plate
19 for rotation about vertical axes, the rollers
contacting the rear face of the flange 10 of the
upper rail 5. A vertical bracket arm 22 is posi- 55

tioned centrally between the rollers 21, 21 but in front of the track A. This bearing arm is rigidly connected at its upper end to the plate 19, and journaled on the lower end thereof is a bearing 5 roller 23 which contacts the front edge of the lower rail 6. Thus the rollers 21, 21 and 23 cooperate with the vertical track A to maintain the carriage D in a horizontal plane and also permit said carriage to move either to the right or left 10 along said track. The plate 19 is formed with a longitudinal slot 24 which is disposed directly above the supporting rod B, and extends inwardly from the right hand end thereof. The plate is also formed with an opening 25 which is located 15 directly in rear of the slot 24 and adjacent the right hand end thereof, the slot and the opening being in communication with each other.

The carriage feeding means E is manually operable to feed the carriage intermittently to 20 the right along the track. To this end, the upper edge of the flange 10 of the upper rail 5 is provided with a series of ratchet teeth 26 which extend substantially throughout the entire length thereof. A spring pawl 27 is secured to a carrier 25 28 which is slidably mounted in guides 29, 29 located on the upper face of the carriage plate 19 for longitudinal movements relative thereto, the pawl projecting downwardly through an opening 30 formed in the plate 19 for engagement with 30 said ratchet teeth. A finger knob 31 is attached to the pawl for facilitating the disengagement of the same from said teeth when it is desired to return the carriage along the track to its initial position. A lever 32 is positioned on the plate 35 19 on the right of the opening 25 and is fulcrumed intermediate its ends to swing about a vertical pivot 33, the rear arm 34 of the lever having a pin and slot connection 35 with the pawl carrier 28. A link 36 extends longitudinally of the carriage 40 and has its right hand end pivotally connected as at 37 to the rear arm 34 of the lever 32. The left hand end of the link 36 is pivotally connected as at 38 to the rearwardly extending arm 39 of a bell crank lever 40 which is fulcrumed as at 41 to the plate 19 on the left of the slot 24. The 45 other arm 42 of the bell crank lever has a pin and slot connection 43 with the rear end of a horizontal pull rod 44 which is slidably mounted in guides 45, 45 attached to the plate 19, the pull rod being disposed above an elongated slot 46 formed in the plate. Rigidly secured to the under face of the rod 44 and projecting downwardly through the slot 46 is a lug 47, Fig. 9, having a vertically disposed slot 48 forming a resultant fork. Rigidly 50 secured to and depending from the front portion of the carriage plate 19 in front of the supporting rod B, is a pair of spaced bearing arms 49, 49 in which is journaled a horizontal rock shaft 50. Fixed to the left hand end of the shaft 50 is an upwardly extending rock arm 51 which carries a horizontal pin 52 at its upper end for sliding engagement in the slot 48 of the pull rod 44. A coil spring 53 has one end connected to the pivot 38 on the arm 39 of the bell crank lever 40 and its other end connected as at 54 to the forward arm 55 of the lever 32. This spring functions to retain yieldably the pawl in its normal retracted or non-feeding position, and also to retain yieldably the pull rod 44 at the forward end of its stroke. 60 A stirrup 56 is connected to the lower end of a chain 57 which is trained over a pulley 58 rotatably mounted on the under face of the carriage plate 19, the chain thence extending rearwardly and having its rear end connected to the lug 47 65 75 of the pull rod 44. It will therefore be seen that

the rock arm 51 is normally at the rear end of its stroke, that when the stirrup 56 is depressed the pawl 27 will remain stationary in engagement with the associated tooth 26 and the lever 32 will swing about the pivot connection 35 thereby tensioning the spring 53 and moving the carriage D one step to the right, and that upon release of the stirrup the spring will return the parts to their initial positions during which time the lever 32 will swing about its fulcrum 33.

The looping mechanism F includes a horizontally reciprocatory needle 59, a horizontally reciprocatory loop spreader 60, and a loop retainer 61. The needle 59 is slidably mounted in guides 62, 62 on the carriage plate 19 located in front of the slot 24 and is movable across said slot and into the opening 25, the needle path thus being in a plane at right angles to the direction of movement of the carriage. The rear end of the needle is pointed and is provided with an eye 63 for receiving the thread or twine 17. The needle is disposed above an elongated slot 64 formed in the carriage plate 19. Rigidly secured to the under face of the needle and projecting downwardly through the slot 64, Fig. 8, is a lug 65 having a vertically disposed slot 66 forming a resultant fork. Fixed to the right hand end of the rock shaft 50 is an upwardly extending rock arm 67 which carries a horizontal pin 68 at its upper end for sliding engagement in the slot 66. Thus 30 when the stirrup 56 is depressed to feed the carriage one step to the right, the needle is moved rearwardly across the slot 24 until the eye 63 is well into the opening 25. The loop spreader 60 is slidably mounted in a guide 69 on the carriage 35 plate 19 located in rear of the slot 24 and on the right of the opening 25, and is movable in a plane at right angles to the plane of the needle movement. The left end of the spreader is pointed, and the reciprocatory movement of the spreader 40 is such that the pointed end traverses the needle path and passes over the needle, Fig. 12. The right hand end of the spreader is connected to the front arm 55 of the lever 32 by a pin and slot connection 70. Thus when the stirrup 56 is released to effect a feeding of the carriage and a return or forward movement of the needle, the spreader 60 will be moved to the left, the point of the spreader passing in front of the needle eye. A vertically disposed needle plate 71 is disposed between the slot 24 and the opening 25, and is provided with a downwardly extending slot 72 for receiving the needle. The left wall 73 of the needle slot 72 is located in close proximity to the needle. The left end of the needle plate is bent to form an ear 71a which is attached to the carriage plate 19, and the right hand end of the plate is bent to form the spreader guide 69. The retainer 61, which is below the spreader 60, is in the form of a bell crank lever, is fulcrumed to 50 swing about a vertical pivot 74 on said spreader, and comprises arms 75 and 76, the arm 75 being pointed and constituting a retainer arm. A vertical stop pin 77 is mounted on the carriage table in a position to be engaged alternately by the arms 75, 76 of the retainer during each reciprocation of the spreader 60 and thereby rock the retainer.

The left hand end of the supporting rod B is formed with a slot 78, as shown in Fig. 14, to receive and anchor the free end of the thread or twine 17.

In operation, let it be assumed that several tobacco hands have been successively placed against the supporting rod B and alternately on 75

opposite sides thereof and the hands secured together by a connected series of enchain loops 16, as shown in Fig. 1. In this figure, the carriage has been fed one step but the stirrup 56 5 has not been released, the needle has entered the previously formed loop which had extended around the spreader, and the spreader has just cast off said loop around the needle. Upon release of the stirrup, the spring 53 will swing the lever 32 which will retract the pawl 27 to its initial position, and also move the spreader 60 to 10 the left whereby said spreader will enter the needle loop. During this movement of the spreader, the retainer arm 75 will also enter said 15 loop and immediately thereafter the arm 76 will contact the stop 77 and effect a rocking of the retainer 61, as shown in Fig. 12, whereby said arm 75 will be moved to the right and will carry the loop therewith. Simultaneously with the 20 spreader entering the loop, the needle begins its forward movement to shed said loop onto the spreader. When the needle 59 and the spreader 60 have completed these strokes, they are in the positions shown in Fig. 13. The operator then 25 places a tobacco hand in position on the support B with the stems bearing against the leg of the loop which extends from the needle, as shown in dotted lines in Fig. 13. The operator then depresses the stirrup 56, the carriage D is moved 30 one step, the needle 59 is moved rearwardly on the right hand side of the stems and into the loop which is around the spreader 60 and retainer 61, and the spreader is returned to its initial 35 position shown in Fig. 1 during which time the retainer has been swung about its pivot 74 to permit the loop to be shed therefrom.

It is of course to be understood that the details of structure and arrangement of parts may be variously changed and modified without departing from the spirit and scope of my invention.

I claim:—

1. In a tobacco looping machine, the combination with a support for tobacco hands, of a loop forming mechanism mounted in cooperative relation to said support, and means for effecting a relative feeding movement between the support and the loop forming mechanism and for actuating the latter, said loop forming mechanism comprising a reciprocatory needle and a reciprocatory spreader movable in a horizontal plane above the support and in planes at right angles to each other.

2. In a tobacco looping machine, the combination with a stationary horizontally disposed supporting rod for tobacco hands, of a stationary track arranged in parallelism therewith, said track being provided with a series of ratchet teeth extending longitudinally thereof, a carriage movable along said track and above the supporting rod, a loop forming mechanism mounted on said carriage, and means for intermittently feeding the carriage along the track and for actuating the loop forming mechanism, said feeding means including a pawl movably mounted on the carriage for cooperation with said ratchet teeth.

3. In a tobacco looping machine, the combination with a stationary horizontally disposed supporting rod for tobacco hands, of a stationary track arranged in parallelism therewith, said track being provided with a series of ratchet teeth extending longitudinally thereof, a carriage movable along said track and above the supporting rod, a loop forming mechanism mounted on said carriage, and means for inter-

mittently feeding the carriage along the track and for actuating the loop forming mechanism, said feeding means including a pawl movably mounted on the carriage for cooperation with said ratchet teeth, a lever mounted on the carriage and connected to the pawl, a bell crank lever fulcrumed on the carriage, a link connecting the pawl lever and one arm of the bell crank lever, a spring connecting said pawl lever and said bell crank arm, and manually operable means connected to the other arm of said bell crank lever.

4. In a tobacco looping machine, the combination with a stationary horizontally disposed supporting rod for tobacco hands, of a stationary track arranged in parallelism therewith, said track being provided with a series of ratchet teeth extending longitudinally thereof, a carriage movable along said track and above the supporting rod, a loop forming mechanism mounted on said carriage, and means for intermittently feeding the carriage along the track and for actuating the loop forming mechanism, said feeding means including a pawl movably mounted on the carriage for cooperation with said ratchet teeth, a lever mounted on the carriage and connected to the pawl, a bell crank lever fulcrumed on the carriage, a link connecting the pawl lever and one arm of the bell crank lever, a spring connecting said pawl lever and said bell crank arm, a pull rod slidably mounted on the carriage and connected to the other arm of the bell crank lever, a pulley journaled on the carriage, a stirrup, and a flexible connection extending over the pulley and connected at its ends to the pull rod and to the stirrup.

5. In a tobacco looping machine, the combination with a stationary horizontally disposed supporting rod for tobacco hands, of a stationary track arranged in parallelism therewith, a carriage movable along said track and above the supporting rod, a loop forming mechanism mounted on said carriage and including a horizontally reciprocatory needle movable in a plane at right angles to the direction of carriage travel, and a cooperating horizontally reciprocatory loop spreader movable in a plane at right angles thereto, and means for intermittently feeding the carriage along the track and for actuating the loop forming mechanism.

6. In a tobacco looping machine, the combination with a stationary horizontally disposed supporting rod for tobacco hands, of a stationary track arranged in parallelism therewith and having a series of ratchet teeth extending longitudinally thereof, a carriage movable along said track and above the supporting rod, means for intermittently feeding the carriage along the track including a pawl movably mounted on the carriage for cooperation with the ratchet teeth, a lever mounted on the carriage and connected to the pawl, a rock shaft journaled on the carriage, operating connections between the rock shaft and the pawl lever, a loop forming mechanism mounted on the carriage including a horizontally reciprocatory needle movable in a plane at right angles to the direction of carriage travel, operating connections between the rock shaft and the needle, a horizontally reciprocatory loop spreader cooperating with the needle and movable in a plane at right angles thereto, said spreader being operatively connected to said pawl lever, and means for rocking said shaft.

7. In a tobacco looping machine, the combination with a stationary horizontally disposed sup-

- porting rod for tobacco hands, of a stationary track arranged in parallelism therewith and having a series of ratchet teeth extending longitudinally thereof, a carriage movable along said track and above the supporting rod, means for intermittently feeding the carriage along the track including a pawl movably mounted on the carriage for cooperation with the ratchet teeth, a lever mounted on the carriage and connected to the pawl, a rock shaft journaled on the carriage, operating connections between the rock shaft and the pawl lever, a loop forming mechanism mounted on the carriage including a horizontally reciprocatory needle movable in a plane at right angles to the direction of carriage travel, operating connections between the rock shaft and the needle, a horizontally reciprocatory loop spreader cooperating with the needle and movable in a plane at right angles thereto, said spreader being operatively connected to said pawl lever, means for rocking said shaft, and spring means for returning the pawl, the needle and the spreader to their initial positions subsequent to each feeding movement of the carriage.
8. In a tobacco looping machine, the com-

bination with a support for tobacco hands, of a chain loop forming mechanism mounted in co-operative relation to said support, and means effecting a relative feeding movement between the support and the loop forming mechanism and for actuating the latter to form a connected series of enchain loops embracing and connecting but not penetrating the hands and subject to being unravelled by longitudinal pull without breakage of portions of the hands.

9. In a tobacco looping machine, the combination with a support for tobacco hands, of a chain loop forming mechanism mounted in co-operative relation to said support, and means effecting a relative feeding movement between the support and the loop forming mechanism and for actuating the latter to form a connected series of enchain loops embracing and connecting but not penetrating the hands and subject to be unravelled by longitudinal pull without breakage of portions of the hands, said loop forming mechanism including a needle and a spreader each reciprocable across the path of movement of the other.

DELBERT R. DINKINS.

25
